The ornamental design for a monitor, as shown and described.

DESCRIPTION

FIG. 1 is a perspective view of a monitor, showing my new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is another right-side view of a monitor of FIG. 1, showing a display part of the monitor in a slant position;

FIG. 9 is an enlarged view of the encircled portion A in FIG. 1; and,

FIG. 10 is a rear perspective view of a monitor of FIG. 1. The broken lines are for illustrative purposes only and form no part of the claimed design. The shade lines in the figures show contour and not surface ornamentation. The diagonal lines in the FIGS. 1, 2 and 9 represent a reflective surface.
